UNITED STATES PATENT OFFICE.

GEORGE H. FRENCH, OF NORTH ATTLEBOROUGH, MASSACHUSETTS, AS-
SIGNOR TO RILEY, FRENCH & HEFFRON, OF SAME PLACE.

DESIGN FOR A CHAIN.

SPECIFICATION forming part of Design No. 31,545, dated September 26, 1899.

Application filed August 17, 1899. Serial No. 727,590. Term of patent 31 years.

To all whom it may concern:

Be it known that I, GEORGE H. FRENCH, a citizen of the United States, residing at North Attleborough, Bristol county, Massachusetts, 5 have invented and produced a new and original Design for Chains, of which the following is a specification, reference being had to the accompanying drawing, forming a part hereof.

My design consists in a loop of the chain 10 having the ends thereof brought together at one point, from which point parts of the chain extend parallel and directly adjacent to each other, these parallel portions being joined at their ends, and from the point of junction a 15 single chain-section extends, terminating in an enlarged piece.

In the drawing the loop A is shown with its ends meeting at one point, at which point is located the tie B. From this point portions

of the chain extend parallel with each other 20 and in a direction diametrically with respect to the loop. These parallel portions are directly adjacent to each other, and they are connected at their ends, a catch C being located at this point. From the point of attachment of the parallel portions of the chain a 25 single section E of chain extends, and this terminates in an enlargement D.

What I claim is—

The design for a chain herein shown and de- 30 scribed.

In testimony whereof I affix my signature in presence of two witnesses.

GEORGE H. FRENCH.
